UNITED STATES PATENT OFFICE.

LEOPOLD AUTHIER, OF ROSEMONT, QUEBEC, CANADA.

CABINET FOR TALKING MACHINES OR THE LIKE.

Application filed April 17, 1922. Serial No. 553,889.

To all whom it may concern:

Be it known that I, LEOPOLD AUTHIER, a British subject, residing at 398 Second Avenue, Rosemont, in the Province of Quebec, in the Dominion of Canada, have invented certain new and useful Improvements in Cabinets for Talking Machines or the like; and I do hereby declare that the following is a true, clear, and exact description of the same.

The present invention relates to improvements in cabinets for talking machines or the like, as set forth in the following description and illustrated in the accompanying drawings.

In the drawings:

Figure 1 is a front view of the improved cabinet.

Figure 2 is a side elevation of Figure 1.

Figure 3 is a cross section through the cabinet.

Like numerals of reference indicate corresponding parts in each figure.

Referring to the drawings, 1 is the cabinet frame and 2 is the rear panel which is preferably of wood. 3 and 4 are the side panels which are of transparent material, such as colored or painted glass, 5 are the door frames and 6 are panels in said frames, preferably also of transparent material similar to the side panels.

Inside said cabinet, is arranged the record rack 7, the back wall of which is preferably of oval or semi-circular cross-section shape, the object being to provide a free space 8 at the rear and sides of the cabinet, and in said free space 8 are suitably secured the electric lamps 9 for lighting the cabinet from the inside. The result is that

wonderful light effects can thus be obtained through the colored transparent panels of the cabinet.

In the front of the cabinet at the upper end of the disk rack is also provided an electric lamp 10 which illuminates the door panels as well as the record rack.

What I claim as my invention is:

1. A phonograph cabinet, embodying side and rear panels, and front door panels, the side panels and the door panels being constructed of transparent material; a record rack within the interior of the cabinet having a vertical wall of substantially semi-circular cross-section which is spaced from the side and rear panels; lighting devices disposed in the space between said side and rear panels and said rack wall to illuminate the entire surface area of the side panels; and a lighting device in the front part of the cabinet adjacent the top of the rack to illuminate the door panels and the rack.

2. A phonograph cabinet, embodying side and rear panels, and front door panels, the side panels being constructed of transparent material; a record rack within the interior of the cabinet having a vertical back wall of substantially semi-circular cross-section which is spaced from the side and rear panels; and lighting devices disposed in the space between said side and rear panels and said rack wall to illuminate the entire surface area of the side panels.

Signed at Montreal, Quebec, Canada, this 28th day of March 1922.

LEOPOLD AUTHIER.
